US00D813212S

(12) **United States Design Patent** (10) **Patent No.:** **US D813,212 S**
(45) **Date of Patent:** **** Mar. 20, 2018**

(54) **NETWORK DEVICE**

- (71) Applicant: **eero inc.**, San Francisco, CA (US)
- (72) Inventors: **Paul Nangeroni**, San Francisco, CA (US); **Paul Kelley**, San Francisco, CA (US); **Nicholas Reid**, San Francisco, CA (US); **Nathaniel C. Hardison**, San Francisco, CA (US); **Nicholas S. Weaver**, San Francisco, CA (US); **Timothy Amos Schallich**, San Francisco, CA (US)
- (73) Assignee: **eero inc.**, San Francisco, CA (US)
- (**) Term: **15 Years**
- (21) Appl. No.: **29/583,542**
- (22) Filed: **Nov. 7, 2016**
- (51) LOC (11) Cl. **14-03**
- (52) U.S. Cl. **USPC D14/240; D14/358**

CLAIM

We claim the ornamental design for a network device, as shown and described.

DESCRIPTION

FIG. 1 is an isometric view, from the front right, of the top of the network device;

FIG. 2 is a plan view of the top of the network device;

FIG. 3 is an elevation view of the front of the network device;

FIG. 4 is an elevation view of the right of the network device;

FIG. 5 is an elevation view of the back of the network device;

FIG. 6 is an elevation view of the left of the network device;

FIG. 7 is a plan view of the bottom of the network device; and,

FIG. 8 is an isometric view, from the back left, of the bottom of the network device.

The broken lines show portions of the network device that form no part of the claimed design.
